UNITED STATES PATENT OFFICE.

LOUIS ALING, OF ZEALAND, MICHIGAN.

IMPROVEMENT IN BUREAU-WASHSTANDS AND COMMODES COMBINED.

Specification forming part of Letters Patent No. 124,653, dated March 19, 1872.

To whom it may concern:

Be it known that I, LOUIS ALING, of Zealand, in the county of Ottawa and State of Michigan, have invented a new and useful Improvement in Bureau-Washstand and Commode; and I do declare that the following is a true and accurate description thereof, reference being had to the accompanying drawing and to the letters of reference marked thereon and being a part of this specification, in which—

Figure 1 is a front elevation of my piece of furniture closed. Fig. 2 is a like view open, and showing the bowl and pitcher. Fig. 3 is a perspective, showing the device open as a commode or closet.

Like letters refer to like parts in each figure.

The nature of this invention relates to an improvement in what are usually denominated bureau-washstands, so arranged that in addition to its legitimate use, it forms also a commode or closet—a very convenient and useful piece of furniture, especially for the sick room. The invention consists in the construction and arrangement of the various parts, as more fully hereinafter described.

In the accompanying drawing, A represents the front of a stand, finished to imitate draw-

ers. The lid or top B is hinged at the back so as to be opened upwardly, and the section of the front composing the two upper draw-panels is, in turn, hinged to the lid, so that when the latter is opened, the former will fold against the lower side of the lid, as shown in Figs. 2 and 3, exposing a chamber, C, to receive the bowl and pitcher, as seen in Fig. 2, standing upon a bottom, D. This bottom D is so arranged that it, in turn, may be raised, (the bowl and pitcher having been removed,) when a seat, E, is exposed. The vessel F may be secured to this seat in such a manner that the seat and vessel may be withdrawn, the seat being secured to the draw-front G for that purpose; or the vessel may be placed upon the floor of the device, and when necessary withdrawn through the draw-front G.

What I claim as my invention, and desire to secure by Letters Patent, is—

The washstand and commode combined, wherein the front A, the lid B, the chamber C, the bottom D, the seat E, and drawer G are constructed and arranged substantially as described and shown.

LOUIS ALING.
